United States Patent

Des. 241,340
Patented Sept. 7, 1976

241,340

SOLID STATE DC SERVO CONTROLLER

Donald H. Jones, Kenneth R. Wyman, and Joseph A. Russo, Pittsburgh, Pa., assignors to Control Systems Research, Inc., Pittsburgh, Pa.

Filed Nov. 7, 1973, Ser. No. 413,597

Term of patent 14 years

Int. Cl. D13—03

U.S. Cl. D26—5 R

Fig. 1

Fig. 2

FIG. 1 is a perspective view of a solid state DC servo controller showing our new design; and

FIG. 2 is an elevational view of the side of our solid state DC servo controller opposite the side shown in FIG. 1.

The rear end of our solid state DC servo controller is flat and unornamented.

We claim:

The ornamental design for a solid state DC servo controller, as shown and described.
